FRAME EMBROIDERY MACHINE

Kurt Scheibel, Dresden, Germany, assignor to
"Würker", Dresden, GermanyApplication August 11, 1937, Serial No. 158,599
In Germany September 3, 1936

21 Claims. (Cl. 112—86)

The present invention relates to an improvement in the frame embroidery machine described in Patent No. 2,050,780 granted August 11, 1936.

While in the arrangement described in the said prior patent on the setting of the totalling member (means for adjusting the amount of displacement of the frame) with the aid of the plate needles a large number of intermediate members for the setting of the totalling member according to the design are necessary between the plate needles and the totalling member, the number of these intermediate members in the present arrangement is considerably reduced.

This result is attained in accordance with the invention by this that the plates set by the jacquard card are themselves movably mounted on the carriage and provided with projections which according to the setting of the plates come into engagement with levers on the carriage movement in the one direction and the totalling member is operated by the resulting lever movement.

In the embodiment illustrated the levers are T-shaped and mounted on a common axis. The arms of the T-shaped levers are so directed that they extend away from one another. They engage in the totalling member which is mounted in the arm of one of the T-levers.

By this arrangement it is possible with slight swinging movements of the levers to effect a comparatively large displacement of the totalling member. In addition there is the possibility of moving the levers in the same or in opposite directions and thus of obtaining in a simple manner different settings of the totalling member.

As the to and fro movements of the carriage are small the speed with which the carriage moves to and fro can also be kept small. In consequence accelerating and retarding shocks in the machine are avoided. The operation of the machine is therefore extraordinarily silent although it operates at higher speed than the arrangement described in the said prior patent. The arrangement can be such that the movement of the T-shaped levers is initiated by means of the projections on the plates. The levers are engaged in projections on the carriage and are moved thereby in its movement. Thus it is possible to avoid unnecessary strains on the plates and to make them light so that a reduction in weight of the reciprocating parts is obtained.

In order to ensure uniform position of the totalling member the levers are anchored in their normal position. This anchorage is effected by means of pawls which prevent swinging of the

T-shaped levers. These pawls are also operated by the plates. It is however also possible in lieu of employing separate locking pawls to anchor the levers by means of the plates themselves.

As the plates take part in the reciprocating movement of the carriage they are themselves separate from the plate needles which are mounted in the frame.

The carriage itself is formed as a coupling member between pivoted levers and consequently guide tracks, which are more difficult and more tedious to produce than links and bores, are avoided.

The arrangement is operated by means of a known drive which is so arranged that the crank and therewith the levers and carriage remain at rest on setting of the plates.

As in the present device the reciprocating movements of the carriage coact with the levers which control the setting of the totalling member, the exact setting of the embroidery frame depends essentially on the exactness with which the carriage is guided to and fro.

When in consequence inexactitudes occur in the displacement of the carriage these act also on the setting of the embroidery frame.

In order to exclude such want of exactness or to keep it within serviceable small limits it is recommended to displace the crank arm which engages in the carriage not directly by means of a known drive but to interpose between the carriage and the cam disc a toggle lever which is so arranged that its extended position lies parallel to the direction of reciprocation of the carriage or coincides with it.

In this way any lack of exactness which may be for example in the cam guide and may result due to wear cannot become noticeable in the reciprocating movement of the carriage but these inexactitudes are expressed in more or less great bending movement of the toggle. Even when these inexactitudes are comparatively great a hardly noticeable difference will occur in the direction of movement of the carriage and therefore the interposition of the toggle lever tends even with long operating periods to provide great exactitude in the movement of the carriage.

One embodiment of the invention is illustrated in the accompanying drawings.

Fig. 1 shows in elevation the construction of the device.

Fig. 2 is a plan view of Fig. 1.

Fig. 3 shows essentially the same device as in Fig. 1 with a toggle lever interposed in the drive of the carriage.

Figs. 4 and 5 show the T-shaped levers lying behind one another in Fig. 1.

Figs. 6 and 7 show the plates disposed behind one another in Figs. 1 and 2.

5 Fig. 8 shows the totalling member partly covered in Fig. 1.

Fig. 9 shows the carriage.

Fig. 10 shows diagrammatically a setting of the totalling member in which the downwardly extending T-shaped lever has retained its central position and the upwardly projecting T-shaped lever is swung to the right.

Fig. 11 shows in diagrammatic form the setting of the totalling member in which the upwardly extending lever has maintained its middle position and the downwardly extending lever has swung to the left in the direction of Fig. 11.

In Fig. 12 is shown a setting of the totalling member in which the upper lever is swung to the right and the lower lever to the left.

Fig. 13 shows a setting of the totalling member in which both levers have swung to the left.

In the present invention as in the prior patent the embroidery frame is displaced in the movement of the reciprocating carriage. By the carriage movement the T-shaped levers are displaced and according to their setting there is a particular position of the totalling member. On the movement of the carriage in the one direction the totalling member is swung out of its normal position and on the movement of the carriage in the other direction the totalling member is again returned to its normal position. The amount by which the totalling member is moved out of its normal position determines the amount of displacement of the embroidery frame.

The displacement of the levers which influence the position of the totalling member is effected by means of plates which in known manner are displaced by plate needles. On one lever act two plates. Since two levers are necessary for one totalling member, four plates are required for the one totalling member.

In the frame 1 of the machine the levers 2 and 3 are rotatably mounted at 4 and 5. Both levers 2 and 3 engage in the carriage (Fig. 9) by means of pins at 6 and 7 in such manner that the carriage becomes the coupling member. The swinging to and fro of this coupling member is effected by means of the cam disc 8 which is fixed on the driving shaft 9 and according to its path moves up and down a pin 10 projecting into the same which pin is mounted on the lever 3.

The carriage 11 (Fig. 9) is also swung to and fro according to the movement of the lever 3 and in its movement carries therewith the parts mounted thereon. These consist of the plates 12 and 13 (Figs. 6 and 7). They are guided in guide tracks 14, 14a, 14b, 14c of the carriage and can be displaced in the guide tracks by the plate needles 15 and 16 by means of the jacquard card 17.

These plates have separate projections 12, 12a, 13, 13b, and recesses which co-operate with corresponding projections on the T-shaped levers 18 and 19. If for example as shown in Fig. 1, the plate 12 is displaced to the right its projection 12a comes over the projection 18a of the T-shaped lever 18. Up and down movement of the carriage is so controlled by means of the cam disc 8 that at the moment of displacement of the plates the carriage remains at rest. If after displacement of the plate 12 into a position in which the projections 12a and 18a are in register the carriage is moved, the projection 12a comes against the opposite part 18a of the lever 18. This is rotat-

ble about the pivot 20 in the frame. On downward movement of the carriage the projection 18b is swung to the right as indicated diagrammatically in Fig. 10. No change is made in the position of the T-shaped lever 19 on co-operation of the parts as shown in Fig. 10.

The lever 18 has at its upper end a pivot 21 which engages a recess 22a in the totalling member 22. The totalling member 22 is rotatably mounted at its bore 23 on a pivot pin 24 of the lever 19. The position of the totalling member is thus dependent on the position of the pivots 21, 24 of the T-shaped levers 18, 19 as shown diagrammatically in Figs. 10 to 13. In this diagrammatic illustration is shown how the totalling member with its pivot 25 can be brought from zero position into four different positions which lie on one side of the zero position. The symmetrical positions of Figs. 10 to 13 are possible and accordingly four other positions of the pivot 25 of the totalling member.

The totalling member must in order to be capable of assuming the different positions have a recess 60 in which the pivot 28 lies about which pivot the two levers 18, 19 rotate.

The form of the plates is so selected that on their displacement only the projection 18a or 18b of the lever 18 comes in engagement with a corresponding projection on a plate. In other words the one plate—in Fig. 1 the front plate—serves only to turn the lever 18 in clockwise direction and the other rear plate in the opposite direction. A safety device must be provided so that both plates are not displaced simultaneously such movement of the levers 18, 19 can take place only in one direction. In order to displace a lever two plates are thus necessary. As the setting of the totalling member makes two levers necessary there must be present for the two levers two pairs of plates such as shown in Fig. 2.

In order to obtain exact embroidery work a precise setting of the totalling member is necessary. T-shaped levers 18 and 19 are therefore anchored in their normal position. For this purpose locking pawls 26, 27 are used. Locking pawl 26 engages from beneath under the projecting part of the stop 18a and the locking pawl 27 bears from above also against this part 18a. Both locking pawls are rotatably mounted on the frame on an axis 29. They are operated by the plate movement and engage for this purpose with pins 30, 30' in recesses 31, 31' provided in the plates. These recesses are so formed that on the downward movement of the carriage and the downward movement of the plates thereby produced, the pin 30 can slide within the recess 31 without displacement of the locking pawl 26 taking place.

When however the plates are horizontally displaced in the carriage operation of the locking pawls 26, 27 is effected in such manner that the plate which rotates the lever 18 in clockwise direction also releases the locking pawl 26, which in the engaged position prevents rotation of the lever in this direction. In the same manner the other plate which produces rotation of the lever 18 in counterclockwise direction, releases the locking pawl 27 which prevents rotation of the lever 18 in this direction.

The conditions in connection with the lever 19 are exactly the same as with the lever 18. The plates and locking pawls are formed in the same manner and operate in the same manner. As they lie behind one another they are not visible in Fig. 1.

In the foregoing description it is explained

5 how the rotary movements of the levers 18, 19 are operated through the medium of the plates. The plates bear with their projections on the corresponding opposing projections on the levers 18 and 19 and on downward movement of the carriage being initiated the plates will then lie with their projections on the opposing projections of the levers and rotate them. The displacement of the levers is effected in this manner.

10 In order to keep small the parts reciprocating with the carriage, the plates are made light. In the foregoing embodiment they only initiate movement of the levers 18 and 19. In this movement the levers position the correspondingly shaped projections or lugs 32, 32', 33, 33' which cooperate with the projections 34, 35 of the carriage. When engagement is effected the carriage takes charge of the rotation of the levers.

15 20 As already explained above by the displacement of the levers the totalling member with its pivot 25 is brought into definite position (Fig. 13). When the carriage then begins its rearward movement again the totalling member is returned to normal position. According as it has been moved into the position 1, 2, 3 or 4 (Fig. 25 13), the return movement into normal position differs. This return movement of different amount into normal position is transmitted to 30 the connecting rod 36 and this again transmits it to the double armed lever 37 which swings about the pivot 38 and on its free end carries a toothed segment 39.

35 According to the amount of swinging movement of the pivot 25 of the totalling member the toothed segment 39 will be given a rotary movement of different amount about the pivot 38, on return of the totalling member into its normal position again.

40 45 When the totalling member has moved out of normal position this toothed segment 39 is moved out of engagement with the pinion 40. On the return movement of the totalling member into its normal position it is however in engagement with the pinion 40. For this purpose the pivot 38 of the toothed segment is connected to a bell crank lever 41 which can turn about the axis 42 fixed in the frame. It carries a pin 43 which engages in a cam track 44 provided on the cam disc 45. The cam disc 45 is mounted on the axle 46 which is mounted in the frame and is driven in any known manner.

50 55 The cam track 44 is so formed that it produces a reciprocating motion of the pin 43 about the pivot 42, which produces an up and down movement of the axis 38. The toothed segment 39 is thus alternately coupled and uncoupled from the pinion 40.

60 The rack bar which effects displacement of the embroidery frame is displaced by the pinion 40. It is therefore clear that for exact displacement of the embroidery frame, unnecessary play in the pinion 40 must be avoided. Therefore care is taken that when the toothed segment 39 is released from engagement, the pinion 40 is locked. For this purpose the locking pawl 47 is provided which has a locking tooth 47a which locks the pinion 40. This locking pawl 47 can turn about the axis 48 fixed in the frame. It is also formed as a bell crank lever which carries a pin 49 at its short end. This pin 49 engages in a cam track 50 which is also provided on the cam disc 45. The two cam tracks 44 and 50 are so determined with respect to one another that the locking tooth 47a locks the pinion 40 at the mo-

5 ment when the toothed segment 39 is disengaged. At the moment however at which the toothed segment 39 comes into engagement again with the pinion 40, the locking pawl 47a releases the pinion 40.

10 As the setting of the totalling member is effected by means of levers comparatively small swinging movement of the levers can effect a large displacement of the totalling member. The rotation of the levers is produced by the reciprocating movement of the carriage which corresponding to the small rotary movement which is imparted to the levers is also kept within reasonable limits. As an advantage of the small movement of the carriage, small movements of 15 mass are produced and therefore the device can operate at high speed. On the other hand the small movement of the carriage which is transmitted on the displacement of the frame into a large one requires precise movement of the carriage. Unnecessary play in the carriage must therefore in all cases be avoided and care must be taken that such undesired play does not occur when the device has been for a long time in 20 operation.

25 Lack of exactness merely can be caused by wear of the cam tracks which effect the raising or lowering of the lever arm 3 (Fig. 1). In Fig. 3 is shown a construction in which a toggle lever 51 is interposed in front of the crank arm. It is actuated by means of the connecting rod 53 and the bell crank lever 55 rotatable about the axis 54 fixed in the frame. The bell crank lever 55 carries at its free end a pin 56 which engages in a cam track 57 in the cam disc 58 which is firmly 30 connected with the axle 59 rotatably mounted in the frame. The axle 59 is driven, e. g. in any known manner. When the cam disc 58 rotates there is imparted to the bell crank lever 55 an oscillating movement about its pivot 54 and thereby the connecting rod 53 is also driven and from it the toggle lever 51, 52. The dotted lines in Fig. 3 show the position of the toggle lever in retracted position and the full lines in the extended position. If now in consequence of 35 wear of the parts which displace the toggle lever, the toggle lever 51, 52 is swung over its dead point position or is moved not quite to its dead point position, variations in this position are hardly noticeable at the crank arm 3. The arrangement of the toggle lever in front of the crank arm so that the extended position of the toggle lever lies 40 parallel to the direction of reciprocation of the carriage serves also to decrease the inexactness of movement of the carriage and to render harmless wear which might occur with long use.

45 The toggle lever link also relieves pressure on the cam drive and prevents any premature wear. This means can also therefore be employed for the operation of other driving means.

50 I claim:

55 1. In an automatic mechanism for embroidery machines, a mechanism controlled by a jacquard card for determining the displacement of the embroidery frame comprising a carriage, means for reciprocating said carriage, plates mounted upon said carriage, means cooperating with a jacquard card for setting said plates, levers actuated by said plates and a totalling member set in accordance with the actuation of said levers 60 whereby the amount of displacement to be given to the embroidery frame is determined.

65 2. In an automatic mechanism for embroidery machines, a mechanism controlled by a jacquard card for determining the displacement of the 70

- embroidery frame comprising a carriage, means for reciprocating said carriage, plates mounted upon said carriage, means cooperating with a jacquard card for setting said plates, levers pivoted at a fixed point actuated by said plates and a totaling member set in accordance with the actuation of said levers whereby the amount of displacement to be given the embroidery frame is determined.
10. 3. In an automatic mechanism for embroidery machines, a mechanism controlled by a jacquard card for determining the displacement of the embroidery frame, comprising a movable carriage, plates mounted upon said carriage, means operating with a jacquard card for setting said plates, levers actuated by said plates and a totaling member set in accordance with the actuation of said levers whereby the amount of displacement to be given the embroidery frame is determined.
15. 4. In an automatic mechanism for embroidery machines, a mechanism controlled by a jacquard card for determining the displacement of the embroidery frame comprising four way motion elements cooperating with the jacquard pins and being set thereby and a totaling member set in accordance with the setting of said elements by said pins whereby the amount of displacement to be given the embroidery frame is determined.
20. 5. In an automatic mechanism for embroidery machines, a mechanism controlled by a jacquard card for determining the displacement of the embroidery frame comprising four way motion elements cooperating with the jacquard pins and being set thereby and a pivotally mounted totaling member set in accordance with the setting of said elements by said pins whereby the amount of displacement to be given the embroidery frame is determined.
25. 6. In an automatic mechanism for embroidery machines, a mechanism controlled by a jacquard card for determining the displacement of the embroidery frame comprising four way motion elements cooperating with the jacquard pins and being set thereby, movable levers actuated by said elements and a totaling member actuated by said levers whereby the amount of displacement to be given the embroidery frame is determined.
30. 7. In an automatic mechanism for embroidery machines, a mechanism controlled by a jacquard card for determining the displacement of the embroidery frame comprising four way motion elements cooperating with the jacquard pins and being set thereby, movable levers actuated by said elements and a totaling member pivotally mounted on said levers actuated by said levers whereby the amount of displacement to be given the embroidery frame is determined.
35. 8. In an automatic mechanism for embroidery machines, a mechanism controlled by a jacquard card for determining the displacement of the embroidery frame comprising horizontally slideable plates, means for vertically reciprocating said plates, means cooperating with a jacquard card for setting said plates horizontally, levers pivoted at a fixed point cooperating with said plates upon the vertical reciprocation of said plates and means cooperating with said levers for determining the displacement to be given to the embroidery frame.
40. 9. In an automatic mechanism for embroidery machines, a mechanism controlled by a jacquard card for determining the displacement of the embroidery frame comprising horizontally slideable plates, means for vertically reciprocating
45. said plates, means cooperating with a jacquard card for setting said plates horizontally, levers pivoted at a fixed point cooperating with said plates upon the vertical reciprocation of said plates and a pivoted member cooperating with said levers for determining the displacement to be given to the embroidery frame.
50. 10. In an automatic mechanism for embroidery machines, a mechanism controlled by a jacquard card for determining the displacement of the embroidery frame, comprising a movable carriage, movable plates upon said carriage having projections thereon, pivoted levers actuated by said projections and a totaling member set by said levers whereby the amount of displacement to be given to the embroidery frame is determined.
55. 11. In an automatic mechanism for embroidery machines, a mechanism controlled by a jacquard card for determining the displacement of the embroidery frame, comprising a movable carriage, plates slidably mounted on said carriage, means cooperating with a jacquard card for setting said plates, T shaped levers mounted on a common shaft cooperating with said plates and means cooperating with said levers for determining the amount of displacement to be given to the embroidery frame.
60. 12. In an automatic mechanism for embroidery machines, a mechanism controlled by a jacquard card for determining the displacement of the embroidery frame, comprising a movable carriage, plates slidably mounted on said carriage, means cooperating with a jacquard card for setting said plates, T shaped levers mounted on a common shaft cooperating with said plates, a totaling member cooperating with said levers and means cooperating with said totaling member for displacing an embroidery frame in accordance with the setting of said totaling member.
65. 13. In an automatic mechanism for embroidery machines, a mechanism controlled by a jacquard card for determining the displacement of the embroidery frame, comprising slideable plates actuated by the jacquard pins, levers mounted upon a common shaft cooperating with said plates, a totaling member pivotally mounted at spaced points in adjacent levers and means cooperating with said totaling member for displacing an embroidery frame in accordance with the setting of said totaling member.
70. 14. In an automatic mechanism for embroidery machines, a mechanism controlled by a jacquard card for determining the displacement of the embroidery frame, comprising a carriage, means for reciprocating said carriage, plates slidably mounted in said carriage adapted to be set by the jacquard pins, T shaped levers having oppositely directed arms cooperating with said plates and a totaling member pivotally mounted in arms of said T shaped levers whereby a displacement of the embroidery frame may be secured in accordance with the setting of said totaling member.
75. 15. In an automatic mechanism for embroidery machines, a mechanism controlled by a jacquard card for determining the displacement of the embroidery frame, comprising movable plates adapted to be set by the jacquard pins, said plates having projections thereon, pivoted levers adapted to cooperate with said projections, means for locking said levers except when actuated by said projections and a totaling member cooperating with said levers whereby the amount of displacement to be given to an embroidery frame is determined.

16. In an automatic mechanism for embroidery machines, a mechanism controlled by a jacquard card for determining the displacement of the embroidery frame, comprising a carriage, means for reciprocating said carriage, slidable plates upon said carriage adapted to be set by the jacquard needles, said plates having projections thereon, pivoted levers cooperating with said projections so that initial movement is imparted to said levers by said projections, means upon said carriage cooperating with said levers after initial movement has been imparted thereto in order to positively move said levers and a totaling member set by the movement of said levers whereby an embroidery frame may be displaced in accordance with the setting of said totaling member.

17. In an automatic mechanism for embroidery machines, a mechanism controlled by a jacquard card for determining the displacement of the embroidery frame, comprising a series of slidable plates adapted to be set by the jacquard pins, a series of pivoted levers cooperating with said plates, a totaling member actuated by said levers which determines the amount of displacement to be given to an embroidery frame and means for locking the plates of said series of plates not actuated by the jacquard pins.

18. In an automatic mechanism for embroidery machines, a mechanism controlled by a jacquard card for determining the displacement of the embroidery frame, comprising a reciprocating carriage, slidable plates adapted to be set by the jacquard pins mounted upon said carriage, movable levers cooperating with said plates, a totaling member actuated by said levers whereby the amount of displacement to be given to an embroidery frame is determined and means actuated by said plates for locking said levers.

19. In an automatic mechanism for embroidery machines, a mechanism controlled by a jacquard card for determining the displacement of the embroidery frame, comprising a carriage, a pivoted lever to which said carriage is pivotally connected, a cam for oscillating said lever whereby a reciprocating motion is given to said carriage, slidable plates mounted upon said carriage adapted to be actuated and set in predetermined position by the jacquard pins and a totaling member adapted to be set in predetermined position by the setting of said plates whereby a displacement of an embroidery frame may be secured in accordance with the setting of said totaling member.

20. In an automatic mechanism for embroidery machines, a mechanism controlled by a jacquard card for determining the displacement of the embroidery frame, comprising a carriage, a toggle link mechanism for reciprocating said carriage, sliding plates mounted upon said carriage adapted to be set by the jacquard pins in accordance with a predetermined design and means cooperating with said plates for determining the displacement to be given to an embroidery frame.

21. In an automatic mechanism for embroidery machines, a mechanism controlled by a jacquard card for determining the displacement of the embroidery frame, comprising a carriage, a pivoted link to which said carriage is pivotally connected, a toggle link also pivotally connected to said link, cam means for actuating said toggle link whereby a reciprocatory motion is given to said carriage and means determining the displacement to be given to an embroidery frame co- operating with said carriage.

KURT SCHEIBEL.
